UNITED STATES PATENT OFFICE.

FRANCIS M. UHLER, OF LINCOLN, NEBRASKA, ASSIGNOR OF ONE-HALF
TO GEORGE W. DAVIS, OF LINCOLN, NEBRASKA.

INTERNAL-COMBUSTION ENGINE.

No. 815,492.

Specification of Letters Patent.

Patented March 20, 1906.

Application filed December 23, 1904. Serial No. 238,142.

To all whom it may concern:

Be it known that I, FRANCIS M. UHLER, a citizen of the United States, residing at Lincoln, in the county of Lancaster and State of Nebraska, have invented a new and useful Internal-Combustion Engine, of which the following is a specification.

This invention relates to internal-combustion engines, and has for its principal object to provide an engine of simple and economical construction wherein all vibration will be taken up, the end thrusts in opposite directions being neutralized by a pair of oppositely-moving pistons disposed in the same cylinder.

A further object of the invention is to improve and simplify the construction of this class of devices by lessening the number of parts, by removing all of the inlet and exhaust valves commonly employed, and by so arranging the parts that the engine may be lubricated conveniently and thoroughly and may be readily repaired when necessary.

With these and other objects in view, as will more fully hereinafter appear, the invention consists in certain novel features of construction and arrangement of parts herein-after fully described, illustrated in the accompanying drawings, and particularly pointed out in the appended claim, it being understood that various changes in the form, proportions, size, and minor details of the structure may be made without departing from the spirit or sacrificing any of the advantages of the invention.

In the accompanying drawings, Figure 1 is a sectional elevation of an internal-combustion engine constructed in accordance with the invention. Fig. 2 is an end elevation of the same. Fig. 3 is a sectional view of the engine cylinder and piston, illustrating a slight modification of the invention.

Similar numerals of reference are employed to indicate corresponding parts throughout the several figures of the drawings.

The engine-frame includes a base or bed 10, that is provided with standards 11, at the top of which are suitable bearings for the support of a double crank-shaft 12. Suitable balance-wheels 13 are provided at the opposite ends of the shaft 12, as usual, and one or both of these may be employed as belt-wheels for the transmission of power.

The base or bed forms a support for a cylinder 15, the central portion of which is disposed immediately under the crank-shaft. The opposite ends of this cylinder are closed by heads 16, carrying stuffing-boxes 17 of any ordinary construction, and the cylinder is provided with a water-jacket 18, through which water may be circulated in the usual manner. In the cylinder are arranged two hollow pistons 20, each carrying a pin 21, on which is fulcrumed one end of a connecting-bar 22. The opposite end of the bar is connected to one arm of a lever 23, and the opposite arm of the latter is connected by a rod 24 to one of the cranks of the crank-shaft. The cranks are arranged at diametrically opposite points, and the pistons move toward and from each other. In the outer end of each piston is secured a ring 25, and to this is secured the inner end of a tube 26, that encircles the connecting-rod 22. The outer portion of the tube passes through the stuffing-box 17, and the diameter of said tube is such that perfect freedom of movement is permitted during the slight vertical play of the outer portion of said connecting-rod. The space between the two pistons forms a compression and explosion chamber, and the space between the opposite faces of the pistons and the heads of the cylinder form pumping-spaces into which the explosive mixture is drawn as the pistons return on the compression-stroke.

Leading into each of the cylinders is an inlet-port 28, through which the explosive mixture passes, the port being so located that during the inward compression-stroke of the piston a partial vacuum will be created in the outer end of the cylinder, and as soon as the port is covered the explosive mixture will quickly flow through such port and fill the cylinder. On the outward stroke of the piston the explosive compound from both cylinders will be forced through ports 30 into a passage 31, that communicates through one or more ports 32 with one end of the explosion-chamber of the engine, this port 32 being uncovered when the piston has reached the limit of its outward movement, and the inlet-port may be considered as one terminus of the explosion-chamber. At the opposite end of the explosion-chamber is an escape-port 33 of much larger area than the inlet-port, and it is uncovered in advance of the

- opening of said inlet-port, so that the exploded gases may pass more quickly from the cylinder. The direct passage of the incoming explosive mixture from the inlet-port 32 to the discharge-port 33 is prevented by deflectors 35, which cause the incoming gases to travel in a swirling path that will clear the cylinder of the gases exploded by the previous operation.
- 10 In the operation of the engine the pistons shown in Fig. 1 are at the end of the inward compression-stroke and the charge is about to be ignited by a sparking plug 36 or in any other suitable manner. The spaces at the 15 ends of the cylinders have been filled with an explosive compound entered through the ports 28. When the explosion occurs, the two pistons will be driven, respectively, in opposite directions, and the explosive compound will be forced from the ends of the cylinders through the ports 30 into the passage or passages 31. When the pistons reach or nearly reach the limit of their outward movement, the exhaust-port 33 will be opened 20 and a portion of the exploded gases will instantly escape. Slight further outward movement will then uncover the inlet port or ports 32, and the gases will pass through said ports and strike against the deflectors 35, and traveling in a swirling path will drive the exploded gases toward the exhaust-port 33. On the reversal of the movement of the pistons the gases will be compressed until the pistons again assume the position shown in 25 Fig. 1, at which time the second explosion will occur. During the second inward movement of the pistons vacuums or partial vacuums will be formed in the outer ends of the cylinder, and as soon as the ports 28 are uncovered a fresh quantity of explosive charge 30 will fill the outer ends of said cylinders.
- In Fig. 3 is illustrated a slight modification of the invention, wherein the structure remains precisely the same as that previously 35 described, with the exception that a suction inlet-valve 40 is arranged in communication with the passage 31'; but in this case the ports 28', leading to the outer ends of the cylinders, are at the extreme ends of said cylinders, the device operating on the suction-stroke to draw in a charge to be subsequently compressed and exploded.

It will be seen that all superfluous valves

and other members have been discarded and that by reducing the number of working parts and simplifying the construction of the engine there is less likelihood of break downs and repairs, and at the same time by so arranging the pistons that they simultaneously move in opposite directions, respectively, all 55 end thrust and vibration is taken up and the engine may be used to advantage on automobiles, launches, and like structures where rapid vibration from the engine is not desirable.

Having thus described the invention, what is claimed is—

The combination in an internal-combustion engine, of a frame, a crank-shaft journaled in said frame, a cylinder arranged below the shaft, said cylinder having heads at its opposite ends, stuffing-boxes carried by the heads, a pair of pistons arranged in said cylinder and movable in opposite directions, respectively, tubes connected to the outer faces of the pistons and leading through said stuffing-boxes, the cylinder being thus divided into a central explosion-chamber and end pumping-chambers, inlets through which the explosive mixture may pass to the end pumping-chambers when the pistons are at the limit of instroke, ports leading from said pumping-chambers and connected to a port that is placed in communication with the central explosion-chamber, when the pistons are at the limit of outstroke, one of the pistons controlling the inlet-port, and an exhaust-port leading from the combustion-chamber and controlled by the opposite piston, the ports being disposed, respectively, at opposite ends of said explosion-chamber, connecting-rods leading from the pistons through the tubular portions thereof, brackets extending outward from the frame to points beyond the ends of the cylinder, levers pivoted on said brackets, the lower arms of said levers being connected to the rods, and upper rods extending from the upper arms of said levers to the crank-shaft.

In testimony that I claim the foregoing as my own I have hereto affixed my signature in the presence of two witnesses.

FRANCIS M. UHLER.
